UNITED STATES PATENT OFFICE.

CHARLES H. WINDSOR, OF PALMYRA, NEW JERSEY.

SANITARY BASIN FOR LAVATORIES.

1,379,152.

Specification of Letters Patent. Patented May 24, 1921.

Application filed August 25, 1917. Serial No. 188,146.

To all whom it may concern:

Be it known that I, CHARLES H. WINDSOR, a citizen of the United States, residing at Palmyra, in the county of Burlington and State of New Jersey, have invented new and useful Improvements in Sanitary Basins for Lavatories, of which the following is a specification.

The present invention relates to sanitary basins for use, preferably, in connection with the ordinary stationary wash-basin and all other lavatories of the basin type.

Very often persons become infected with diseases through the misuse of wash-basins especially in hotels, public places and the like, and it is the object of this invention to provide simple and effective means which will permit the use of such basin without fear of infection.

Another object of the invention is the production of a portable and collapsible sanitary wash basin for use primarily, but not necessarily, with the usual lavatories and adapted to be placed thereon in such manner as to receive the water from its faucet and to empty thereinto with facility without contacting with contaminated parts of the lavatory.

The invention consists in the provision of an extensible supporting frame adapted to rest upon the upper edge of the usual wash-basin, a collapsible basin removably and pivotally supported on the frame and having other connection with the frame for maintaining it against pivotal movement, said basin being shiftable on the frame to effect a disengaging of said other connection from the frame, whereby the basin may be swung about its pivot to facilitate the emptying of its contents into the lavatory directly beneath it.

Another feature of the invention resides in the provision of a knockdown supporting frame and a sanitary basin consisting of a ring having secured thereto impervious flexible material which forms the bowl of the sanitary basin, thus permitting the device to be folded and packed in a small space.

Other features and advantages will appear from the following description, and the appended claims.

In the accompanying drawings, which illustrate the preferred embodiment of the invention:

Figure 1 is a perspective view of the invention showing the same applied to a lavatory of the usual construction.

Fig. 2 is a transverse vertical section of the lavatory, shown in Fig. 1, showing the invention applied and its relative position with respect to the parts of the lavatory; the dotted lines showing the basin of the invention emptying into the lavatory.

Fig. 3 is a view similar to Fig. 2, however, showing a slight modification of the invention which adapts it to another type of lavatory.

Fig. 4 is a fragmentary detail sectional view to illustrate the detailed construction of the basin of the invention.

Fig. 5 is a fragmentary detailed construction illustrating the construction of the frame, and

Fig. 6 is a fragmentary detailed construction of the basin of the invention.

Fig. 7 is a fragmentary detail of means for securing the supporting elements and the basin together.

Like characters denote similar and like parts throughout the specification and drawing.

With particular reference to Figs. 1 and 2, A denotes an extensible knockdown frame, preferably rectangular, and consisting of a pair of end bars 1 and a pair of side bars 2. The side bars 2 each consist of two telescoping members 2' and 2'', having their outer ends formed with a transversely extending bore in which slidably extends the ends of the bars 1. Suitable securing members, such as thumb screws 3, are provided for adjustably securing bars 1 and 2 and the telescoping members 2' and 2'' in their adjusted positions. A supporting frame, thus provided, is extensible and may be adjusted for use in connection with lavatories of various sizes, as the frame is to be laid upon the top of the lavatory and to be supported upon and adjacent the upper edge of its bowl.

The sanitary basin member B comprises an annular member consisting of two nested rings 4 and 5 between which is gripped and held, the edge of a flexible water-proof material 6 which forms the bowl of the basin B. The outer ring 5 is provided at substantially diametrically opposite points with lugs or supporting arms 7 to rest upon two opposite side bars of frame A, when the latter is suit-

ably adjusted, as shown in Figs. 1, 2 and 3. The basin B is adapted to lie over and partially extend into the bowl of the lavatory and to receive water from its faucets. However, the basin B is to be of such size that its bowl portion 6 will not contact with the bowl of the lavatory for sanitary reasons.

To maintain the basin B in a fixed position relative to the frame and against pivotal movement on the arms 7, the latter are so formed as to slightly suspend the basin from the frame in order that opposite portions 8 of the basin may engage the underside of the other two side bars of the frame, as in Figs. 1 and 2. This arrangement, moreover, permits the contents of the basin B to be readily emptied without necessitating the removal of the frame from the lavatory or the removal of the basin from the frame, by simply shifting or sliding the basin on the bars 1 of the frame so that the end portions 8 will be free to permit the basin to pivot about the supporting arms 7, see dotted lines Fig. 2.

The outer ring 5 of the sanitary basin has on its lower edge an inwardly extending annular flange 9. This flange acts as a stop for the inner ring 4 and prevents it from being drawn out of engagement with the ring 5 by the weight which may be placed upon the flexible bowl of the basin B. Furthermore, the flange serves as a gripper for maintaining the edge of the flexible bowl 6 in engagement between the rings 4 and 5, it being noted however, that the edge 10 of the flange is rounded to relieve it of a sharp cutting edge.

In Fig. 3 the basin B may be suspended from the frame A to a greater or less degree by merely adjusting the arms 7 to lengthen or shorten their vertical portions, in order that the water from the faucet will be discharged into the basin, when the invention is used with lavatories of the type wherein the faucet lies directly upon the lavatory slab, as shown, or wherein the faucet may be concealed in the lavatory. Obviously this modification necessitates the provision of a different retaining arrangement to normally maintain the basin B against pivotal movement on its arms 7; and it may be accomplished by any suitable means, such as by an upwardly extending arm 11 secured to one of the rings 4 and 5 between the support-arms 7 and has its upper end laterally recessed as at 14, to receive one of said bars of the frame A. To obtain such an adjustment of the basin relative to the frame, as just mentioned, three perforated lugs 7^a are provided on the outer periphery of the outer ring 5, two of said lugs being arranged diametrically opposite each other to slidably receive portions of the arms 7 while the remaining lug adjustably receives the retaining arm 11. Binding screws

7^b are threaded in the lugs 7^a to frictionally engage and hold the arms 7 and 11 in their adjusted positions.

It may be found convenient and advantageous to thread a thumb screw 12 in the upper end of the retaining arm 11 to bind it in engagement with the bar of said frame after a manner shown in the drawings. It will also be clear that the basin may be swung on the arms 7 to empty it, as in the showing in Fig. 2, by unscrewing the binding screw 12 and shifting the basin B on the frame so that the retaining arm will disengage the latter.

Any suitable water-proof material may be used to provide the bowl 6 of the sanitary basin B. However, it is also contemplated to use paper bowls which may be supplied by hotels or sold through vending machines. It is especially contemplated to provide paper bowls having their peripheral portions stamped or pressed, in the manner shown in Fig. 4, so that they may be readily received between the rings 4 and 5 and rest upon the flange 9. The bowl portion 6 of the sanitary basin may be further provided with a discharge opening at its lowermost portion and closed by an appropriate plug of rubber, paper, or the like 13 as shown in Fig. 6.

Applicant however, does not wish to limit himself to the particular material which will form the flexible bowl 6 of the sanitary basin, nor does he wish to limit himself to the use of the invention with the stationary wash basin of the type shown, as the invention may be susceptible to use with various other types of lavatories or may be used, as will be manifest to those in the art, separately and independently of such lavatories.

The foregoing clearly describes the invention. However, it is to be understood that sundry changes in the construction, combination and arrangement of parts may be made that fall within legitimate scope of the appended claims.

What is claimed is:

1. A sanitary basin for use with the usual lavatory comprising a supporting frame bodily movable to and from a position to rest on the lavatory, a basin member pivotally supported by and in non-tilting engagement with the frame, said basin being shiftable on the frame from its pivotal and non-tilting position to permit its contents to be emptied into the lavatory without removing it from the frame or the frame from the lavatory.

2. A sanitary basin for use with the usual lavatory comprising a supporting frame adapted to be positioned to rest on a lavatory rim, and a basin having pivotal and shiftable supporting arms for removable engagement with the frame whereby the basin may be supported by the frame within

- the lavatory and may be shifted and tilted to empty its contents without removing it from the frame or the frame from the lavatory.
- 5 3. A sanitary basin for use with the usual lavatory, comprising a supporting frame consisting of connected side bars bodily removable to and from a position where they rest on the upper edge of the lavatory, a basin member carried by the frame and having shiftable portions engaging the frame to pivotally support it thereupon and having other portions engaging the frame to maintain the basin against pivotal movement until shifted.
- 10 4. A sanitary basin for use with the usual lavatory, comprising a supporting frame consisting of connected side bars to rest on the upper edge of the lavatory, a basin member having portions engaging the frame to pivotally support it thereupon and having other portions engaging the frame to maintain the basin against pivotal movement, said basin being shiftable on the frame to move said latter portions out of engagement with the frame.
- 15 5. A sanitary basin for use with the usual lavatory, comprising, a supporting frame including side bars adapted to rest on the upper edge of the lavatory, a basin member to be placed over the lavatory and having arms for pivotally supporting the basin on the frame, the edge portions of the basin being adapted to engage certain of said side bars of the frame to retain the basin fixed relative to the latter, said basin being shiftable on the frame whereby said edge portions thereof may be moved out of retaining engagement with the frame.
- 20 6. A device of the character described comprising a supporting frame adapted to rest upon a lavatory, a basin member having diametrically arranged arms for pivotally and shiftably supporting the basin on the frame and having other connection with the frame for retaining the basin against pivotal movement, said basin being adapted to be shifted bodily and to pivot on the said arms to empty its contents into the lavatory when said other connection is disengaged.
- 25 7. A device of the character described comprising an extensible frame adapted to be adjusted to rest upon the upper edge of lavatories of varying sizes and bodily movable to and from a lavatory, and a basin member supported by said frame to lie over the lavatory, said basin member being shiftable and pivoted on and relative to the frame to empty its contents into the lavatory.
- 30 8. A device of the character described comprising a rectangular frame made up of extensible and knock-down portions adapted to be bodily moved to and from a position where it will rest on a lavatory rim, a basin member formed of nested circular rings, one of which is provided with pivotal and shiftable supporting arms engaging said frame to suspend said basin member within the lavatory in a normally non-tilting position, and a bowl member of flexible material secured between said nested rings.
- 35 In testimony whereof I have hereunto set my hand in presence of two subscribing witnesses.
